(57) **CLAIM**

We claim the ornamental design for a round cantilever umbrella base, as shown and described.

DESCRIPTION

FIG. 1 is an upper perspective view of a round cantilever umbrella base.

FIG. 2 is lower perspective view thereof;

FIG. 3 is a top view thereof;

FIG. 4 is a bottom view thereof;

FIG. 5 is a left view thereof;

FIG. 6 is a right view thereof;

FIG. 7 is a front view thereof; and,

FIG. 8 is a back view thereof.

1 Claim, 6 Drawing Sheets
